JESSE A. DUBBS, OF PITTSBURGH, PENNSYLVANIA, ASSIGNOR TO ROBERT J. DUNHAM,
OF CHICAGO, ILLINOIS.

TREATING OIL.

1,100,717.

Specification of Letters Patent. Patented June 23, 1914.

Application filed November 9, 1905. Serial No. 286,471.

To all whom it may concern:

Be it known that I, JESSE A. DUBBS, residing at Pittsburgh, in the county of Allegheny and State of Pennsylvania, a citizen 5 of the United States, have invented or discovered certain new and useful Improvements in Treating Oil, of which improvements the following is a specification.

The invention described herein relates to 10 certain improvements in the distillation of hydro-carbons and has for its object the maintenance of the fluid at a temperature at which a breaking up of the hydro-carbon occurs and at which the hydrogen will combine with the oxygen, mainly or solely by 15 the heat developed by such chemical change or combination.

In the accompanying drawings forming a part of this specification is shown in section 20 elevation a form of apparatus adapted to the practice of my invention.

In the practice of my invention the hydro-carbon oil *i. e.* petroleum or oils identified with petroleum is charged into a retort or 25 vessel 1 having a suitable connection to a condenser 2. This liquid hydro-carbon, if it contains any water, is first treated preferably by heat to drive off such water. The water may be removed as described in application 30 No. 286,472, filed November 9th, 1905, or in any other suitable manner known in the art. After the water is driven off, the temperature of the hydro-carbon is increased, provided the temperature required 35 for driving off the moisture is not sufficient, to start a generation of gases which by preference should be free. This generation of the hydro-carbon gases or vapors will be indicated by the flow of distillate from the

40 condensing coil. The hydro-carbon can be heated to the required temperature to produce hydro-carbon vapor in any suitable manner as by the external application of heat to the containing vessel, by a steam coil 45 in the vessel or by forcing hot air through the hydro-carbon. The temperature employed may vary from 100 F. to 600 F. dependent upon the character of the hydro-carbons treated. I have found that as soon

50 as the hydro-carbon reaches a temperature at which a breaking up or decomposition in the presence of air thereof occurs, that a portion of the hydrogen will combine with the oxygen of air forced through the hydro-carbon by perforated pipe 3 connected to a

suitable pump. This combination of hydrogen and oxygen will produce sufficient heat, if sufficient volumes of air be forced through the material not only to maintain the hydro-carbon at an initial breaking-up temperature, but also to raise it to the temperature required for a further breaking-up. Hence after the dehydrogenation of the hydro-carbon which produces water by the combination of the oxygen of the air and hydrogen from the hydro-carbon begins as will be evidenced by the appearance of water with the other distillate, no heat except that produced by the combination of the oxygen of the air with the hydrogen, etc., of the hydro-carbon is required and cold air can be used for completing the distilling operation. It is found in practice that as the breaking-up and evaporation proceeds, larger volumes of air are required to obtain and maintain the desired rise in temperature for a complete evaporation of the hydro-carbon.

It is characteristic of my improvement that after the heating necessary to start the breaking-up of the hydro-carbon whereby the hydrogen is placed under conditions favorable to combination with the oxygen, no further heat need be applied, the chemical combination of the oxygen and hydrogen supplying sufficient heat which will be proportional within certain limits to the amount of air supplied to the hydro-carbon and which will be generated uniformly throughout the body of the material treated.

When it is desired to prevent a discoloration of the residuum or to bleach the latter as in the manufacture of lubricating oils, steam may be forced through the material while being treated with the air.

I claim herein as my invention:

1. As an improvement in the art of distilling hydro-carbons, the method herein described which consists in heating the material to a point at which the hydro-carbons would be broken up if mingled with air, forcing air through the same and maintaining the heat by the chemical reaction produced.

2. The method of dehydrogenating hydrocarbons which consists of passing air through them when heated to a temperature at which the oxygen of the air will unite with the hydrogen of the hydro-carbon, then continuing the operation by passing through the hydro-carbon a sufficient quantity of air

to cause by the chemical action a desired temperature for so continuing distillation.

3. The method of dehydrogenating hydrocarbons which consists of passing air 5 through them when heated to a temperature at which the oxygen of the air will unite with the hydrogen of the hydro-carbon, then continuing the operation by passing through the hydro-carbon a sufficient quantity of air 10 to cause by the chemical action alone a desired temperature for so continuing distillation.

4. The method of dehydrogenating hydrocarbons which consists of passing air 15 through them when heated to a temperature at which the oxygen of the air will unite with the hydrogen of the hydro-carbon, then continuing the operation by passing through the hydro-carbon a sufficient quantity of air 20 to cause by the chemical action a desired temperature and regulating the temperature of distillation of the hydro-carbon by regulating the quantity of the air passed into it.

5. The method of distilling hydro-carbons 25 which consists of passing air through them when heated to a temperature at which the oxygen of the air will unite with the hydrogen of the hydro-carbons, then continuing the operation by passing through the residue 30 a sufficient quantity of air to maintain by chemical action a sufficient heat to carry on the distillation.

6. The method of distilling hydro-carbons without the use of external heat which 25 consists of passing air through the hydro-carbons while inclosed in a still and at a temperature at which the oxygen of the air will unite with the hydrogen of the hydro-car-

bon, then continuing the operation by passing through the hydro-carbons a sufficient 40 quantity of air to maintain by the chemical action a desired internal temperature to carry on distillation.

7. The method of distilling hydro-carbons which consists of heating the hydro-carbons 45 in a still to a temperature at which the oxygen of the air will unite with the hydrogen of the hydro-carbons, then forcing through the hydro-carbons a quantity of air sufficient to maintain this temperature and such 50 higher temperatures as may be necessary to complete the distillation, and then withdrawing the primary fire and completing the distillation by the use of the internal heat produced by chemical action alone. 55

8. The method of treating hydrocarbons, which consists in passing air through them when initially heated to a temperature at which the oxygen of the air will react on the hydrocarbon, then continuing the operation 60 by passing through the hydro-carbon a sufficient quantity of air to cause by the chemical action alone the desired temperature for maintaining the necessary reaction, without the agency of any substantial external application of heat, and regulating the temperature required for the reactions by regulating the quantity of air passed into the hydrocarbons. 65

In testimony whereof, I have hereunto set 70 my hand.

JESSE A. DUBBS.
